UNITED STATES PATENT OFFICE.

CARL T. MEYER, OF BIRMINGHAM, ALABAMA.

DESIGN FOR AN AUTOMOBILE TAG.

Application filed May 14, 1928. Serial No. 26,656. Term of patent 7 years.

To all whom it may concern:

Be it known that I, CARL T. MEYER, a citizen of the United States, residing at Birmingham, in the county of Jefferson and State of Alabama, have invented a new, original, and ornamental Design for Automobile Tag, of which the following is a specification, reference being had to the accompanying drawing, forming a part thereof, in which—

Fig. 1 is a front elevation of an automobile tag, showing my new design.

Fig. 2 is an edge view thereof.

What I claim is:

The ornamental design for an automobile tag substantially as shown.

In testimony whereof I, CARL T. MEYER, affix my signature.

CARL T. MEYER.
